UNITED STATES PATENT OFFICE.

MARY G. HATCH, OF NEW YORK, ASSIGNOR TO M. H. BIRGE & SONS, OF BUFFALO, NEW YORK.

DESIGN FOR WALL-PAPER.

SPECIFICATION forming part of Design No. 22,941, dated November 28, 1893.

Application filed October 21, 1893. Serial No. 488,820. Term of patent 3½ years.

To all whom it may concern:

Be it known that I, MARY G. HATCH, a citizen of the United States, residing at New York, in the county and State of New York, 5 have invented and produced a new and original Design for Wall-Paper, of which the following is a specification.

The design consists of sprays of flowers and leaves of buttercups and daises grouped together and arranged at certain distances apart upon a striped back ground as represented in the accompanying drawing.

The border or upper portion of the design is formed of festoons of the same flowers and leaves connected by bows of ribbon with a 15 wide band below separating the border from the hanging as shown.

What I claim is—

The design for wall paper herein shown and described. 20

Witness my hand this 14th day of October, 1893.

MARY G. HATCH.
